SHOESHINE FIXTURE

James G. Nevin, Toronto, Ontario, Canada

Application April 15, 1944, Serial No. 531,161

3 Claims. (Cl. 15—267)

My invention relates to improvements in appliances for use in the cleaning and polishing of footwear, and particularly appertains to the novel construction and arrangement of a fixture adapted to hold a boot or shoe firmly while it is being polished.

The invention has as a paramount object the provision of a fixture which will support and clamp a shoe firmly against shifting, so that a person may more easily and conveniently shine his shoes and impart a desirable high polish thereto, which is awkward to accomplish when a shoe is not held securely against movement.

The invention has as a further object the provision of a fixture of this character including a clamping device for engaging the sole and heel of a shoe, which is actuated by a pull-rod having self-locking means.

The invention has as a still further object the production of a shoeshine fixture having means by which it may be readily clamped to the seat of a chair or other support that may be suitable for the mounting of the fixture at a height convenient for the cleaning and polishing of shoes, and one that is suitable for household use.

A distinctive feature of the invention is that it automatically adjusts itself to different sizes of shoes and to either shoe of a pair. The invention is simple to operate and comparatively inexpensive to manufacture.

Having described the major objects and advantages of the invention, other objects and advantages will be manifest from the description in detail hereinafter given and the drawing annexed hereto.

In the drawing there is shown the selected embodiment of the invention in which:

Fig. 1 is a top plan view of the fixture.

Fig. 2 is a longitudinal view thereof partly in section and substantially taken along the line 2—2 of Fig. 1.

Fig. 3 is a cross section thereof taken on line 3—3 of Fig. 2.

Fig. 4 is a cross section thereof on line 4—4 of Fig. 2.

Fig. 5 is a plan view of the cam plate and the inner heel plate.

Fig. 6 is a perspective detail of the outer heel plate and its connection with the pull rod.

Fig. 7 is a sectional detail of the front guide for the pull rod.

Like numerals of reference indicate corresponding parts in each of the figures throughout the drawing of the invention.

My invention embodies a top plate 10 suitable

for supporting the sole portion of a shoe. This plate carries means for gripping the sole and the heel portions, and is desirably equipped with an attachment device by which it may be conveniently clamped to the seat of an ordinary chair or equivalent object that may be utilized to support the fixture at such a height that a person may stand upon one foot and rest the other foot on the fixture for conveniently carrying out the cleaning and polishing operation. The attachment device may be of any approved form, but that shown in the drawing by way of illustration but not limitation consists of a C-shaped clamp 11 having a thumbscrew 12 and being connected to the forward end of the top plate by spaced brackets 13, and being connected to the rear of the top plate by a vertical wall 14, which may be a downturned continuation thereof.

The means for gripping the sole of a shoe comprises a pair of ears 15 having upturned lugs 16 for engaging the side edges thereof at the part of the shoe that narrows toward the toe end. The ears are in the form of plates extending toward each other beneath said top plate, and are guidably constrained for inward and outward movement as by means of slots 17 therein loosely engaged by headed pins 18 secured to said top plate. The ears are actuated by a cam plate 19 disposed beneath said top plates and spaced therefrom. The cam plate is guidably constrained to a reciprocable movement lengthwise of said top plate as by slots 20 loosely engaged by pins 21. The cam plate has a pair of cam slots 22 convergently disposed and each loosely engaged by a pin 23 rigidly depending from an ear aforesaid.

It will be gathered that by this arrangement the cam slots 22 function to draw the ears inwardly when the cam plate is urged forwardly, and, conversely, a rearward movement of the cam plate causes the ears to spread.

The means for gripping the heel of the shoe comprises an abutment plate 24 and a heel rest 25. The abutment plate 24 has an upturned shoulder 25' for engaging the breast of the heel, and is attached preferably by a swivel connection 26 to the said cam plate. The swivel connection permits it to swing sidewise so that the shoulder 25' may adjust itself to the angular position of the heel when the shoe is not resting squarely upon the top plate 10.

The abutment plate is operable in an aperture 27 in the wall 14 aforesaid so that it may move with the cam plate lengthwise of the top plate. The heel rest 25 is in the nature of a plate hav-

ing upturned lugs 28 for engaging the rounded back portion of the shoe heel at spaced points. The heel rest is carried by a forwardly extending pull rod 29 of flat material guidably supported intermediate of its length in a slot 30 supplied in the wall 14, and also guidably supported near its forward end 31 in a loop 32. The forward end 31 is curved to provide a pull portion or otherwise devised in a manner to enable it to be conveniently grasped by hand for pulling it forwardly.

Along an edge of a portion of the pull rod that slides in the loop 32 there is provided a series of ratchet teeth 33 adapted for engagement with an element, such as the tooth 34 at a side of said loop, in order to lock the pull rod in any position to which it may be advanced. The ratchet teeth are preferably caused to engage with the tooth 34 automatically as by resiliently pressing the rod toward said tooth, which may be accomplished by the curved leaf spring 35 secured in the loop-opening 36 to bear against the edge of the pull rod opposite said tooth 34—see particularly Fig. 7.

According to the preceding description it will be evident that the fixture is used by placing the sole portion of the shoe upon the top plate 10 and the heel between the abutment plate 24 and the heel rest 25, and then drawing the pull rod 29 forwardly. As the pull rod is thus advanced, the lugs 28 engage the heel and urge the shoe forwardly causing its front edge or breast portion to engage the shoulder 25' of the abutment plate 24. The abutment plate is now urged forwardly along with the shoe, which advances the cam plate 19 thereby drawing the ears 15 inwardly into firm engagement with opposite edge portions of the sole. In the result both the heel and the sole are grasped securely, and the gripping means are locked by the engagement of the tooth 34 with one of the teeth of the rack 33. To release the shoe it is only necessary to press the pull rod away from the tooth 34 and push it rearwardly at the same time.

Since the sole of a shoe commonly recedes from the toe portion on a sharper angle at the outer side, it is desirable that the heel-rest 25 may be capable of swinging laterally to a limited extent so that a shoe for the right foot may be held in a position at a slight angle to one side of the longitudinal axis of the top plate, and the shoe for the left foot may be held at a slight angle to the other side thereof. This results in a more secure engagement of the gripping elements, and is accomplished by pivoting the loop 32 to the top plate as at 37 so that the pull rod may shift laterally in the slot 30. Also, it is desirable that the heel-rest be yieldably mounted on the pull rod in order to assure that no play will exist when a tooth of the tooth-rack thereon is in engagement with the locking tooth 34. This may be achieved by slidably mounting the heel-rest on the pull rod as by the members 38 and interposing a spring 39 between lugs 40 and a stop shoulder 41. The lugs 40 are struck up on the underside of the heel-rest and the stop shoulder 41 is formed by bending downwardly the rear end of the pull rod. The spring 39 is of the leaf type and is secured to the shoulder 41 intermediate of its length, the ends being curved outwardly to engage said lugs 40. By this arrangement the pull rod may be advanced into firm locking engagement with the tooth 34 such as to tension the spring 39.

From the preceding description it will be manifest that the invention provides a practical and serviceable fixture of the kind described and one

which is self adjustable to accommodate shoes of different sizes. Such changes and modifications may be made in the invention as come within the spirit and scope of the appended claims.

What I claim is:

1. A shoeshine fixture comprising a top plate for supporting the sole portion of a shoe, ears slidably mounted at the sides of the top plate for movement to and away from each other, a subtending cam plate mounted for reciprocal movement longitudinally of the top plate, said cam plate having cam surfaces arranged to cause said ears to move inwardly to clamp the sole portion of the shoe when the cam plate is urged forwardly, an abutment plate for engaging the front wall portion of the shoe-heel, said abutment plate being secured to the cam plate for unitary movement therewith a forwardly slidable heel rest having upwardly directed lugs for engaging the rear wall portion of the shoe-heel, a pull rod for urging the heel rest forwardly to cause the heel of the shoe to abut said abutment plate and thus urge the cam plate forwardly, and means for locking the pull rod against retraction so as to retain the heel rest in any position to which it may be advanced.

2. A shoeshine fixture comprising a top plate for supporting the sole portion of a shoe, ears slidably mounted at the sides of the top plate for movement to and away from each other, a subtending cam plate mounted for reciprocal movement longitudinally of the top plate, said cam plate having cam surfaces arranged to cause said ears to move inwardly to clamp the sole portion of the shoe when the cam plate is urged forwardly, an abutment plate carried by the cam plate for engaging the front wall portion of the shoe-heel, a movable heel rest having upwardly directed lugs for engaging the rear wall portion of the shoe-heel, a pull rod by which the heel rest is carried by urging it forwardly to cause the heel of the shoe to abut said abutment plate and thus urge the cam plate forwardly, means whereby the pull rod is guidably supported for endwise movement, said means being so constructed as to provide also for a restricted lateral movement of the pull rod, and means for locking the pull rod against retraction so as to retain the heel rest in any position to which it may be advanced.

3. A shoeshine fixture comprising a top plate for supporting the sole portion of a shoe, ears slidably mounted at the sides of the top plate for movement to and away from each other, a subtending cam plate mounted for reciprocal movement longitudinally of the top plate, said cam plate having cam surfaces arranged to cause said ears to move inwardly to clamp the sole portion of the shoe when the cam plate is urged forwardly, an abutment plate carried by the cam plate for engaging the front wall portion of the shoe-heel, a movable heel rest having upwardly directed lugs for engaging the rear wall portion of the shoe-heel, a pull rod for urging the heel rest forwardly to cause the heel of the shoe to abut said abutment plate and thus urge the cam plate forwardly, and means for locking the pull rod against retraction so as to retain the heel rest in any position to which it may be advanced, the aforesaid structure being characterized in that the pull rod is attached to the heel rest by a connection including a resilient member by which tension is applied on the heel rest when the pull rod is locked.

JAMES G. NEVIN.
